United States Patent Office

Des. 223,538
Patented May 2, 1972

223,538

TABLE

James P. Manning, Deerfield, Ill., assignor to Republic Molding Corporation, Niles, Cook County, Ill.

Filed Oct. 12, 1970, Ser. No. 25,461

Term of patent 14 years

Int. Cl. D6—03

U.S. Cl. D33—14

Fig. 3

Fig. 5

Fig. 4

FIG. 1 is a perspective view of a table embodying the new design;

FIG. 2 is an elevational view of the table of FIG. 1;

FIG. 3 is a plan view of the table of FIG. 1;

FIG. 4 is a bottom view of the table of FIG. 1; and

FIG. 5 is a fragmentary sectional view of the table taken along line 5—5 of FIG. 3.

The remaining three elevational views are identical to the elevational view of FIG. 2.

I claim:

The ornamental design for a table, substantially as shown and described.
